UNITED STATES PATENT OFFICE.

JOSEPH ALFRED EVERELL, OF QUEBEC, AND ERNEST PLAMONDON AND UBALD PLOURDE, OF STE. ANNE DE BEAUPRE, QUEBEC, CANADA.

AUTOMATIC STREET AND STATION INDICATOR.

Application filed September 10, 1920. Serial No. 409,401.

To all whom it may concern:

Be it known that we, JOSEPH ALFRED EVERELL, ERNEST PLAMONDON, and UBALD PLOURDE, all British subjects, residing at 5 Quebec city, Ste. Anne de Beaupre, Ste. Anne de Beaupre, respectively, all in the Province of Quebec, Dominion of Canada, have invented certain new and useful Improvements in Automatic Street and Station 10 Indicators; and we do hereby declare that the following is a full, clear, and exact description of the same.

The present invention relates to improvements in automatic street and station signs, 15 and the main object of the invention is to provide a device of this character that will automatically shift a display sheet upon which the names of the streets or stations are printed.

20 A further object of this invention is to provide a device of simple and cheap construction, which is mechanically operated.

Another object of the invention is to provide a device of this character that may be 25 operated from any suitable place on the car, such as in the rear where the conductor usually stands.

The invention will be readily understood 30 from the accompanying drawings and following description, in which like numerals of reference indicate corresponding parts in each figure.

In the drawings:

Figure 1, is a front elevation of the casing 35 containing the display sheet and operating mechanism.

Figure 2, is a front elevation of the display sheet operating mechanism, one wall of the said casing having been removed to dis- 40 play the inner arrangement of the operating mechanism.

Figure 3, is a cross section on line 3-3 of Figure 2.

Figure 4, is an end view of the casing 45 illustrating the particular bell operating mechanism.

Figure 5, is an inner view of the casing illustrating the lever operating mechanism.

Figure 6, is an enlarged perspective view 50 of the upper end of the ratchet lever, and the reversing handle.

Referring to the drawing, 1 indicates a casing containing two superposed horizontal shafts 3^a which are journaled in suitable 55 brackets mounted therein and carry drums

3 over which is rolled a flexible display sheet 4; the names of the streets or stations printed or otherwise marked on the sheet being brought successively into reading position opposite a sight opening 2 formed in the front wall of the casing.

To effect the feeding of the sheet from one drum to the other, the following mechanism may be provided:—In one of the aforementioned brackets in which the drum shafts 3^a are supported, there is journaled a horizontal shaft 10, adapted to be rotated

step by step by means of a pawl-and-ratchet device (not shown) of conventional type which is enclosed in a casing 11 loosely mounted on the end of shaft 10 and in which an operating lever 12 is fitted; the arrangement being such that when said lever is

swung in one direction (for example, from its full-line position to its dotted-line position, Fig. 3), the pawl-and-ratchet device will turn shaft 10 one step in the same direction.

This movement of the shaft is transmitted through intermeshing gears 9 and 8 to the lower drum shaft 3^a on which gear 8 is mounted, said shaft 3^a being provided with a second gear 7 which is connected through an intermediate gear 6 with a similar gear 7 on the upper drum shaft, so that both drums 3 will be positively driven, one drum winding up and the other drum unwinding the display sheet 4. The intermediate gear 6 is

loosely mounted on a stub shaft 5 carried by the bracket in which shaft 10 is supported.

The operating lever 12 projects through a slot 13 (Fig. 3) in the top wall of the casing 1 and is provided adjacent its free end with a handle 14, by means of which it may be directly shifted. It is preferable, however,

95 to actuate said lever from a distance—for instance from the rear of the car where the conductor usually stands; and with that end in view, the lever is formed with a perforated lug 15 (Fig. 6) to which is connected one end 100 of an operating cord 16 or similar flexible element, the other end of the cord being led through an opening 30 formed in a casing

27 (Fig. 5) located in the rear part of the car. This casing 27 contains two pulleys 28 and 29, the latter of which is situated adjacent opening 30; and the cord 16 is passed

105 over said pulley, then under a pulley 34 attached to a lever 32 pivoted at one end at 31 within said casing, and then over pulley 110

28, and is then connected to lever 32. Hence, when lever 32 is swung down, the operating cord 16 will be pulled to the right (Fig. 3) and will move lever 12 with it in the same direction. To facilitate the operation of lever 32, it may have suspended from it a handle 33, which projects downward through an opening in the bottom of casing 27; and a dash-pot 35 may also be connected 10 with said lever to cushion its return movement when handle 33 is released.

In the construction illustrated, the operating lever 12 makes its active or driving stroke when moving from left to right (Fig. 15 3) and is returned to its initial position by means of a spring 21 which is secured thereto at one end and at the other end to the bottom wall of casing 1; this spring 21 also serving to return the lever 32 to normal 20 position, as will be apparent. During the return movement of lever 12, the pawl-and-ratchet device moves idly; but it is to be understood that, if desired, said device may operate during the return stroke instead 25 of during the outward or initial stroke of the lever, or that suitable reversing means may be employed in connection with the device to enable the winding action to take place on the drum previously acting to unwind the sheet. However, it is sufficient for 30 all present purposes that the operating lever acts as previously described, the precise form of ratchet used not being material to the invention. In any case, the sheet winds 35 up on one drum and unwinds from the other, the winding drum being provided with suitable compensating means, for example a conventional slip clutch, in order to take care of the increasing diameter of one drum and 40 the decreasing diameter of the other. The precise compensating means or device employed likewise forms no part of the actual invention and, hence, has not been indicated.

It will be obvious from the foregoing that 45 at each operation of the lever 12, whether effected directly by means of its handle 14, or by pulling on the cord 16, the sheet 4 will be fed a distance sufficient to bring the next street or station name opposite the opening 50 or window 2. In order to retain the sheet in position after each movement thereof, a locking mechanism, here shown as in the nature of an escapement is provided. The operating lever 12 is accordingly equipped 55 with a cross-rod or bar 20 (Fig. 3) to which are attached the upper ends of a pair of cords 19 whose lower ends are attached to two weighted pawls 18. These pawls 18 are pivotally mounted on the bottom wall of casing 1 and are disposed at opposite sides of 60 a disk 17 which is fixed to the lower drum shaft 3^a and has formed in its periphery two notches or seats in which the free inner ends 65 of the pawls are adapted to alternately engage. When lever 12 is swung from left to

right, for instance, it will exert a pull on the cord 19 connected to the pawl which at that time happens to be engaged with disk 17 and will release that pawl, while at the same time the cord connected to the other or 70 disengaged pawl will become slackened, and the latter pawl will swing into engagement with said disk by reason of its own weight, thus stopping the movement of the display sheet and holding it against displacement. 75 The reverse operation takes place, of course, during the return movement of the lever.

In connection with the mechanism above described, a signal device is preferably employed which audibly indicates the operation of the sheet. This device, as shown, comprises a bell (Figs. 1 and 2) which is adapted to be struck by a hammer 26 carried by a spring-controlled lever 25 (Fig. 85 4), the latter being normally engaged by a trip lever 24. Lever 24 is connected by a link 23 to a disk 22 which is fixed to the projecting end of the lower drum shaft 3^a, all of the parts just described being located 90 exteriorly to the casing 1. Disk 22 will rotate, therefore, with said shaft and, in so doing, will pull down on lever 24, through the intermediary of link 23, thereby causing said lever to trip the hammer lever 25 which, in consequence, strikes against the bell. To insure the parts being in proper 95 position to enable the above-described action to take place each time lever 12 is operated, the aforesaid lower drum shaft has 100 fixed to it a notched disk 24^a (Fig. 2) with which a spring-pressed detent 25^a cooperates. This detent is mounted in a suitable bracket 26^a attached to one of the shaft-supporting brackets within the casing 1, and 105 it is adapted to engage the notched disk 24^a at the end of each complete rotation of the drum shaft, or, in other words, when the parts 22, 23 and 24 have been brought into 110 their respective initial positions.

The display sheet 4 may be illuminated at night by means of electric lights 36 (Figs. 2 and 3) which are suitably arranged within the casing 1 and connected to any desired source of current supply.

We claim as our invention:—

1. In an indicating mechanism of the character described, the combination of a casing having a sight opening therein; a drum shaft journaled in the casing; a drum on said shaft adapted to move a flexible display sheet across said opening; an operating lever connected to impart a step-by-step rotary movement to said shaft and drum; a notched disk on said shaft; a pair of reversely-acting pawls engageable with said disk; and connections between said lever and said pawls for operating the latter in alternation.

2. In an indicating mechanism of the character described, the combination of dis-

play sheet feeding means including an operating shaft; a signal; means connected to automatically operate the signal each time said shaft is turned; and a device operatively related to said shaft for centering the signal-operating means at the end of each movement of the shaft.

3. In an indicating mechanism of the character described, the combination of display sheet feeding means including an operating shaft; a signal; an operating element therefor; a trip lever normally engaged with said operating element; and means on said shaft for actuating said operating element.

4. In an indicating mechanism of the character described, the combination of display sheet feeding means including an operating shaft; a signal; an operating element therefor; a trip lever normally engaged with said operating element; a crank disk on said shaft; and a connection between said disk and the trip lever to actuate the latter during the rotation of the former.

5. In an indicating mechanism of the character described, the combination of display sheet feeding means including an operating shaft; a signal; an operating element therefor; a trip lever normally engaged with said operating element; means on said shaft for actuating said operating element; and a device operatively related to said shaft for centering the last-named actuating means at the end of each movement of the shaft.

6. In an indicating mechanism of the character described, the combination of display sheet feeding means including an operating shaft; a signal; means connected to automatically operate the signal each time said shaft is turned; a centering disk fixed to said shaft to turn therewith; and a detent cooperative with said disk to center the signal-operating means at the end of each movement of the shaft.

7. In an indicating mechanism of the character described, the combination of a casing having a sight opening therein; a pair of parallel drum shafts mounted in the casing in superposed relation; a pair of drums on said shafts adapted to carry a flexible display sheet from one to the other; a gear on each drum shaft; an intermediate gear in mesh with both first-named gears; an operating shaft mounted in the casing; a lever in said casing connected to impart

a step-by-step rotary movement to the operating shaft; means for actuating said lever; a gear connection between the operating shaft and one drum shaft for transmitting the step-by-step movement of the former to the latter; and an escapement operated by said lever for limiting the extent of rotation of that drum shaft.

8. In an indicating mechanism of the character described, the combination of a casing having a sight opening therein; a pair of parallel drum shafts mounted in the casing in superposed relation; a pair of drums on said shafts adapted to carry a flexible display sheet from one to the other; a gear on each drum shaft; an intermediate gear in mesh with both first-named gears; an operating shaft within the casing; a lever in said casing connected to impart a step-by-step rotary movement to the operating shaft; means for actuating said lever; a gear connection between the operating shaft and one drum shaft for transmitting the step-by-step movement of the former to the latter; and means operated by said lever for limiting the extent of rotation of that drum shaft.

9. In an indicating mechanism of the character described, the combination of a casing having a sight opening therein; a pair of parallel drum shafts mounted in the casing in superposed relation; a pair of drums on said shafts adapted to carry a flexible display sheet from one to the other; a gear on each drum shaft; an intermediate gear in mesh with both first-named gears; an operating shaft within the casing; a lever in said casing connected to impart a step-by-step rotary movement to the operating shaft; means for actuating said lever; a gear connection between the operating shaft and one drum shaft for transmitting the step-by-step movement of the former to the latter; and a pair of pawls connected with said lever to be shifted thereby into alternate engagement with an element on said drum shaft to limit the extent of rotation of that shaft.
